UNITED STATES PATENT OFFICE.

LESTER JOHN SEYLER, OF PORT ARTHUR, ONTARIO, CANADA.

STAKE WINDLASS.

Application filed August 29, 1923. Serial No. 660,015.

To all whom it may concern:

Be it known that I, LESTER JOHN SEYLER, a subject of the King of Great Britain, and resident of the city of Port Arthur, in the 5 Province of Ontario and Dominion of Canada, have invented certain new and useful Improvements in Stake Windlasses, of which the following is a specification.

This invention relates to improvements in 10 stake windlasses, and the object of the invention is to provide a device of this character for pulling automobiles out of a ditch or other place where traction is not sufficient to move the car.

15 Further objects are the provision of a device of this kind that can be carried on a car and which will quickly be available for use when required.

With the foregoing and other objects in 20 view, the invention consists essentially in the device an embodiment of which is described in the present specification and illustrated by the accompanying drawings which form part of the same.

25 Referring to the drawings, in which like characters of reference indicate corresponding parts in each figure:

Figure 1 is a perspective view of an embodiment of my invention set up.

30 Figure 2 is a side elevation partly in section showing the device embedded in the ground.

In the drawings, A indicates the device 35 as a whole comprising a hollow metal stake 10 formed with a solid end portion 11 and a pointed extremity 12. This hollow metal member is preferably of cylindrical formation, similar to a pipe, with a pointed end and flat at the upper end at 13 to engage 40 with a suitable ring washer 14.

Into this pipe is fitted a drum post member 15 adapted to form a drum and to rotate within the hollow receiving member 10. The post or drum member 15 is provided 45 adjacent the top with a hole 16 therethrough adapted to receive a turning rod 17.

18 is a retaining stake adapted to be driven into the ground adjacent the hollow member 10 and connected in any suitable

manner, preferably as here shown, by means 50 of a chain 19 with a loose eye ring 20 on the drum post 15 adjacent the top and prevented from moving downwardly by means of a suitable pin 21. The chain and retaining stake are adapted to reinforce the drum 55 member which is designed to rotate within the retaining ring.

22 is a cable preferably of steel, the loose end of which is secured in a hole 23 in the drum post 15 and the other end of which is 60 attached to a car or otherwise (not shown). The rod 17 is then operated to rotate the drum post 15 to wind up the cable and thus exert a pull on the car or other object to 65 which the cable is attached.

As many changes could be made in the above construction and many apparently 70 widely different embodiments of my invention, within the scope of the claim, constructed without departing from the spirit 75 or scope thereof, it is intended that all matter contained in the accompanying specification and drawings shall be interpreted as illustrative and not in a limiting sense.

What I claim as my invention is:

A device of the character described comprising a hollow anchoring stake pointed at one end and open at the other and adapted to be sunk in the ground, a flat top for the open end adapted to engage with a washer, a solid post adapted to fit into and rotate in said stake to form a detachable winding drum, means in the solid post for securing a cable thereto, a ring member loosely mounted on the solid post, a stop member carried by the post to limit the downward travel of said ring, and a retaining chain connecting the ring with a retaining post, an orifice in the solid post adjacent the top 85 between the top and said ring, and a handle 90 adapted to fit into said orifice whereby the solid post is rotated to wind thereon a cable.

In witness whereof I have hereunto set my hand in the presence of two witnesses.

LESTER JOHN SEYLER.

Witnesses:

KATHELEEN HARRIS,
R. L. SEAMAN.
